1 Claim**ABSTRACT OF THE DISCLOSURE**

A window sash construction for a side frame wall unit of a railway vehicle. The side frame of the vehicle defines a window opening from which project a series of roll pins. A plurality of slotted clip members each include a flange which engages the sash unit. Stationary pins project from the frame through the slots in the clips. As the clips are driven relative to the stationary pins, the sash unit is correspondingly cammed into a final position. Additional pins or stops are provided to prevent reverse movement of the clip members.

Prior to this invention windows of railway passenger cars have normally incorporated a sash frame work. The dimension and the tolerances of the frame work have been carefully maintained in order to receive a sash unit of like dimensions. When the sash units and window openings have been of large dimensions the holding of such tolerances has involved difficult procedures. In addition, the physical handling of such larger units has required much care to properly install and seal such units within the framework. Thus, a disadvantage of such large window constructions of the prior art has been the necessity of maintaining close and accurate dimensional tolerances of not only the framework for receiving the sash unit, but also the dimensions of the sash unit per se.

Accordingly, it is the principal object of this invention to provide an improved window sash construction which avoids one or more of the disadvantages of the prior art constructions.

It is another object of this invention to provide an improved window sash construction which enables the window sash unit to be incrementally received and advanced within the window opening defined by the framework of the side wall.

It is still a further object of this invention to provide an improved window sash construction which is designed to minimize or to eliminate visible fastening means for holding the window sash unit in place within the window opening.

For a better understanding of the present invention together with other and further objects thereof, reference is had to the following description taken in connection with the accompanying drawings and its scope will be pointed out in the appended claim.

In the drawings—

FIG. 1 is a vertical elevational inside partial view of a side frame of a vehicle such as a railway car and illustrating the various framing members defining the window opening;

FIG. 2 is a vertical elevational view similar to FIG. 1 but showing the window sash unit removed from the side frame of the vehicle;

FIG. 3 is a vertical sectional view taken along the lines 3—3 of FIG. 1 showing the window sash unit and side frame in cross-section;

FIG. 4 is a perspective view partially in section, and greatly enlarged, showing the initial manner of installation of the window sash unit into the window opening of the side frame;

2

FIG. 5 is a view similar to FIG. 4 illustrating the final position of the sash relative to the frame and the inclusion of interior trim for concealing the fastening beams;

FIG. 6 is an exploded view similar to FIG. 3 showing the relationship of the fastening clips prior to insertion of the window sash unit within the window opening;

FIGS. 7 and 8 are vertical elevational sectional views similar to FIG. 3 but illustrating a modified form of the invention.

Referring now to the drawings, wherein like numerals indicate like parts unless otherwise specified, and particularly in FIGS. 1 and 2, a side frame of a vehicle such as a railway car is generally indicated at 10. The side frame in the present instance is of double girder-like construction and includes an upper girder frame 11 and a lower girder frame 12 spaced vertically apart by stub posts 13 and 14.

The upper girder 11 includes an upper window rail 15 while the lower girder 12 likewise includes a lower window rail 16. The upper and lower window rails are of channel construction and each includes a central horizontally disposed web portion with upstanding spaced flanges disposed therefrom. The stub window posts likewise are of wide channel construction and include a central web which is disposed outboard of the vehicle with inturned spaced flanges integral therewith. The central flanges of window post 13 and 14 and the outermost stub flanges of window rails 15 and 16 serve to support an external sheet skin 17. Upper and lower inner sheathing skin members 18, 19 are shown secured to the opposite flanges of the belt rail members. In addition vertical trim members 20 are disposed between the window posts 13 and 14. The upper and lower belt rails combined with the stub window posts together define margins constituting a window opening W.

With reference now to FIG. 2 there is shown a window sash unit 25 which includes a rectangular sash frame 26, a pair of spaced apart inner and outer window panes 27 and 28. The window panes 27 and 28 are shown secured within the sash frame 26 by means of a flexible glazing strip 29 as seen in FIGS. 4 and 5. The glazing strip 29 may be of a suitable elastic rubber-like material. The rectangular sash frame 26 includes a horizontally disposed web 31 which in turn is formed with a centrally raised shoulder portion 32. The lower portion beneath the central shoulder defines a groove 33 which completely encircles the sash frame 26. The sash frame in addition includes an outboard vertically disposed flange 34 having an upper portion 35 and a lower portion 36. The outer perimeter of glazing strip 29 includes and defines a centrally located groove 37 which completely encircles the glazing strip. The groove 37 is dimensioned so that the glazing strip firmly grips the shoulder 33 on the web of the sash frame 26. The outboard vertical face 38 of the glazing strip makes snug engagement with the inner face of upstanding flange portion 35 of the sash frame member. A suitable body sealing compound 39 may be applied between the outer surfaces of the glazing strip and the mating surfaces of the sash frame.

The inboard portion of the glazing strip includes an inwardly extending tongue portion 40. An interior trim member 43 is secured to the member 43 by its vertical flange 44 in overlapping relation to the lower inner trim. Its horizontal flange 45 extends inwardly and overlaps the top surface of flange 31 of sash 26. The aforementioned tongue 40 in turn overlaps the marginal edge of the horizontal flange 45.

The glazing strip in addition includes a side groove which completely encircles the inboard surface thereof to receive a removal inlay strip 47. Withdrawal of this strip from the body of the glazing ring enables easy re-

removal and insertion of one or both of the window panes 27, 28.

In order to facilitate mounting of the window sash unit 25 within the window opening W defined by the side frame, a plurality of clip members 49 are spaced about the inner peripheral opening of the window frame. Each clip 49 includes a horizontally disposed base portion 51 and an upstanding flange portion 52. The upstanding flange portion 52 is inclined inwardly toward the center of the car a slight amount. As seen in FIG. 4 the flange 52 is shown received within the like slanted slot or groove 33 defined in the shoulder portion 37 of sash frame 26. The base portion 51 of each clip 49 includes an elongated cut-out or slot 53. The axis of each slot is inclined relative to the longitudinal axis of the side frame. During the initial assembly procedure as shown in FIG. 6 the clip 49 is positioned relative to the sash frame 26 with the latter frame positioned outwardly from the side frame 11. It will also be noted that roll pin 55 is removed from the central flange 57 of upper rail 15. Thereafter the sash frame 26 with clips 49 in position thereon are advanced inwardly to the center of the rail car to near seating engagement as shown in FIG. 4. In this position the upright outer flange 26 of the sash is spaced a slight amount from the outer skin 17 as indicated by the distance S. In this further inward position of the sash unit the roll pin 55 is inserted within its hole 59. It will be noted that the hole 59 corresponds in location to the most inboard portion of the slot 53 within flange 51 of the clip. In order to move the entire sash unit 25 to its final position as indicated in FIG. 5, the clips 49 are tapped in a direction as indicated by the arrow X. By virtue of the inclined slot 53 within the clip, it and the sash frame 26 connected thereto is thereafter caused by such movement to be moved in the direction of the arrow Y into bottoming engagement. This final latter position corresponds to the fully bottomed position of the sash unit within the frame. In order to prevent the clips from backing off in a reverse direction, a hole 65 is drilled in window rail 16 just clear of the back edge 67 of the clip. An additional roll pin 63 is driven in the hole 40 and makes contact with the back edge to keep the same in place. It should further be noted that window rail 16 includes elongated holes 68 and trim rail 44 includes holes 69 to permit the flow of hot air upwardly to scan the inner window pane 27.

Referring now to FIGS. 7 and 8, a modified form of the invention is shown. In this embodiment of the invention the window sash unit 75 is shown as including a horizontal web portion 76 and an outboard vertical flange portion 77. The inner perimeter of the sash 75 defines a shoulder for receiving a double paned unit 79 which includes an inner pane 81 spaced from an outer pane 83 by means of a spacer strip 84. A rectangular channelled glazing rubber strip 85 embraces the outer marginal edges of

the panes. The outer peripheral edge surface of the sash 75 includes a groove 89 which receives the aforementioned clips 59 in a manner as set forth in the above description applicable to FIGS. 1 to 6 inclusive. An inboard sash strip 93 having a horizontally disposed slot 95 is provided to make facing engagement with the inboard surface 94 of sash frame 75. The upper portion of sash strip 93 is adapted to make facing engagement with the inner face of glazing member 88 as shown in FIG. 8. The lower portion corresponding to the outermost peripheral edge of the sash framing strip 93 includes a plurality of holes 97 to enable the passage therethrough of screws 98 to secure the strip 93 to the outer sash frame portion 75. A window trim member 99 having a horizontal marginal edge portion 100 is adapted to be received within the aforementioned slot 95. The trim member 99 in addition includes a vertical face portion or flange 101 which in turn is mounted in overlapping surface facing engagement with the inner trim surface 19, being secured thereby with screws 103.

While there has been described what at present is considered to be preferred embodiments of this invention, it will be obvious to those skilled in the art that various changes and modifications may be made therein without departing from the scope of the invention.

What is claimed is:

1. A window construction for a side frame of a vehicle having margins thereof defining a window opening, comprising, a sash unit including window pane means and a sash frame extending therearound, said sash frame including a groove extending about its outer periphery, planar clip means including an upstanding flange which is received within said groove and is movable therealong, said clip means defining an elongated slot disposed at an angle to the plane of said side frame, and means projecting from said margins of said window opening through said elongated slot, whereby movement of said clip means in a direction parallel to the plane of said side frame causes said sash unit to be moved in a direction normal to said plane.
